HARMONIC DAMPER FOR PIANOS

Filed March 12. 1923

2 Sheets-Sheet 2

UNITED STATES PATENT OFFICE.

GEORGES CLOETENS, OF BRUSSELS, BELGIUM.

HARMONIC DAMPER FOR PIANOS.

Application filed March 12, 1923. Serial No. 624,620.

To all whom it may concern:

Be it known that I, GEORGES CLOETENS, a citizen of the Kingdom of Belgium, and resident of Brussels, Belgium, have invented 5 certain new and useful Improvements in Harmonic Dampers for Pianos; and I do hereby declare the following to be a full, clear, and exact description of the invention, such as will enable others skilled in 10 the art to which it appertains to make and use the same, reference being had to the accompanying drawings, and to letters or figures of reference marked therein, which form a part of this specification.

15 This invention has to do with improvements in devices forming the subject of Patent 1,392,244. The said patent relates to musical instruments having means for modifying tones, and comprises pressing 20 members, which are mechanically pressed against the strings at given points along their lengths.

The present invention affords an improved device having pressing members, supported 25 in a novel manner.

It has been proposed to apply pressing members on the strings by means of a system of levers with several pivot points. This arrangement does not always give the 30 necessary rigidity to cause the pressing members to be perfectly immovable, and not vibrate with the strings.

To cure this defect, according to this invention, the pressing members are connected 35 to the cross bars which give rigidity to the string frame. They are connected by pivoted arms, the arms having the pressing members at one end, and being connected to the cross bars by means of hinges.

40 Further, the invention relates to various means for regulating the position of the pressing members, in all directions relative to the strings.

Since the pressing members are mounted 45 on supports rigidly connected to the frame of the instrument by pivoted arms, and that no adjustment of their position is possible, it is necessary, in order to apply the members to the desired points of the strings, 50 to displace their relation to their supports, in all directions.

The invention is illustrated in the annexed drawings, wherein;

55 Fig. 1 is a diagrammatic plan view;
Fig. 2 is a section on A—B of Fig. 1,

looking to the left, and to an enlarged scale;

Fig. 3 is a sectional view of one form of pressing member connection;

Fig. 4 is a sectional view of a second 60 form of pressing member connection;

Figs. 5 and 6 are sectional views of modifications of Figs. 3 and 4 respectively;

Fig. 7 is a view of a modified form of 65 pressing member fixing and actuating device;

Fig. 8 is a section on line E—F of Fig. 7, looking to the right;

Fig. 9 is an elevation of a string adjusting 70 device;

Fig. 10 is a section on line C—D of Fig. 9;

Fig. 11 is a sectional view of a modified 75 form of the device of Fig. 10.

A somewhat more extended description 80 of the figures of drawing, follows, to aid in an understanding of the invention.

Figures 1 and 2 relate to a method of construction of the frame carrying the rigid members which come into contact with the 85 strings.

Figure 1 is a diagrammatic view of the 90 general arrangement of the strings of a piano and of the devices according to the invention.

Figure 3 illustrates a method of fixing 95 a pressing member so as to permit horizontal movements thereof.

Figure 4 illustrates a method of fixing a 100 pressing member permitting horizontal and circular movement thereof.

Figure 5 illustrates a method of fixing 105 the pressing member similar to that of Figure 3 but permitting also of adjusting the height of the pressing member.

Figure 6 illustrates a method of fixing 110 the pressing member similar to that in Figure 4 in the case where the supporting rod is a flexible blade, with a device permitting of adjusting the height of the pressing member.

Figures 7 and 8 illustrate a method of 115 fixing an actuating the pressing members coming into contact with the strings, when the strings are situated underneath or near the cross bars which serve to increase the rigidity of the frame.

Figures 9, 10 and 11 illustrate a device 120 permitting of producing the effect of tight strings in stringed and hammer instruments,

similar to the effects of a harpsicord, cymbal, mandoline, guitar, etc.

In these figures the same elements are indicated by the same reference characters.

5 The object of the devices disclosed in the present application is to permit of modifying the sounds produced by the strings during the whole of a period of playing by the player. These results are obtained by means 10 of pressing members which are applied at determined points of each string.

In the device illustrated in Figures 1 and 2, the supporting members 1 and 1', to which are secured the rigid members 2 which are 15 to be pressed as desired against the strings, are connected to the cross bars 3, which serve to ensure the rigidity of the frame 4 supporting the strings 5, by means of hinges.

20 The attachment of the supporting member 1 to the cross bars 3 is effected by means of arms 6, pivoting in the hinge 7 secured to members 8, in such a manner as to permit of raising the member 1 and thus dis- 25 engaging it neatly from the strings 5.

As regards the lowering of the member 1, this is effected by a metal member 11 in which is provided a groove which is filled with lead 12 or other heavy material along 30 its whole length. Under the action of the weight of the member 1, the rigid members 2 may be pressed energetically against the strings 5 without the intermediary of any mechanism.

35 Raising of support member 1 is effected by wedges 9, having one face pressing against member 1, and the other against a bar 3. The wedges are actuated by triangles 10, operated by hand or any other desired 40 means.

45 Figure 3 shows a device for securing one of the rigid members 2, to be pressed against the strings 5, to the supporting member 1. This method of securing permits of horizontal movement of the rigid member 2, 50 called the pressing member, provided at its end with felt 2', in such a manner as to adjust the position of the said pressing member exactly across the strings which are to be pressed.

55 For this purpose the pressing member 2 is mounted at the end of a curved rod 13 which can slide in holes 14 provided in the supporting member 11. The rod 13 and consequently the pressing member 2 are secured in their definite position by a set screw 15.

60 A modification of this device is shown in Figure 4, wherein, in addition to the horizontal movement of the rod 13 supporting the pressing member 2, a circular movement of the latter around the axis of the pivot 16 is also provided for this pivot also serving as the set screw for holding the rod 13.

65 For this purpose the rod 13 slides in an opening 14 provided in an auxiliary hous-

ing 17 filled with a heavy material 12, capable of turning by means of a boss 18 around the set screw 16 which also serves to hold the rod 13 in position. In this manner the pressing number 2 may be set accurately 70 opposite the string and may strike against the latter at the desired point.

75 Another modification is illustrated in Figure 5. The pressing member secured to the end of the curved rod 13 may be moved relatively to its support 11 and may also be moved slightly towards the string under the action of the screw 34 supported by the support 11.

80 This adjustment in height is effected independently of the adjustment by means of the screwed end of the rod 13.

85 A final modification is illustrated in Figure 6 which, in addition to the adjustments provided for in the case of Figure 4, permits the adjustment of the height of the pressing member 2 secured to the end of the rod 13 which, in the example illustrated, is a curved blade. For this purpose, an arm 24 is held against the support 11 by the pivot 16 also serving as a set screw. At the end 31 of the arm 24 a screwed rod 32, carrying at its lower end a leather hammer 33, is 90 screwed into the support 11. This hammer may be lowered in such a manner as to bend 95 the blade 13 slightly, which produces an adjustment of the height of the pressing member 2.

100 Figures 7 and 8 illustrate a device permitting of placing the pressing members 105 against the strings situated below or near the cross bars 3, that is to say at places where the direct action of the pressing members secured to the supporting member 1 would be difficult if not impossible. In this device 110 the pressing members 2 are no longer placed against the strings on the same side 4 of the supporting member 1 of the frame. A lever 19 is supported by the cross bar 3 by means of the plate 20. This lever can pivot around the rod 21 and is held on this by means of a bolt 22. When the supporting member 1, carrying the pressing members 2, is moved towards the strings 3, it bears through the medium of an adjustable screw 25 against 115 the plate 23 provided at the end of the lever 19. This pivots around 21 in such a manner that the other end of the lever 19, which supports the pressing members, moves towards the strings 5 until the said pressing members strike energetically against these 120 strings 5.

125 Figures 9, 10 and 11 disclose a device in which the pressing members consist of a hard material, metal, ebonite or the like, which is placed near the string in such a manner that the string will strike against this member with more or less force. The efforts produced are similar to those produced by harpsicords, cymbals, harps, etc., 130

and they may be graduated by approaching or withdrawing the hard members.

In the specification of the patent a single hard member has been provided for each series of two or three strings corresponding to the same note. According to the present invention a hard member is provided for each string, each member being capable of being approached towards or withdrawn from the string independently. For this purpose the supporting member 26 (Figures 9 and 10) is of V-shape in which is secured a support 27 serving to support the metal rods 28 of which the end 29', which may come into contact with the string, is of hemispherical (Figs. 9 and 10) or elongated shape (Fig. 11). These metal rods 28 are provided with a threaded portion 29 permitting of adjustment of their distance relatively to the strings with which they may come into contact. The supporting member 26 may be moved towards the strings or be disengaged by means of wedges 30 which are acted upon by means of rods 31 (Fig. 1).

25 Claims:

1. A device for modifying the tone of stringed instruments, comprising, a string supporting frame including cross bars, arms pivoted to the cross bars, a supporting member rigidly mounted on the arms, and pressing members carried by said supporting member.

2. A device for modifying the tone of stringed instruments, comprising, a string supporting frame including cross bars, arms pivoted to the bars, a supporting member rigidly mounted on the arms, pressing members on the supporting member, weights on the supporting member for pressing the pressing members against the strings, and wedges for actuating said supporting members with reference to the strings.

3. A device for modifying the tone of stringed instruments, comprising, a string supporting frame including cross bars, arms pivoted to the bars, a supporting member mounted on the arms, angular rods slidably mounted in said supporting member, press-

ing members carried by the angular rods, and means for adjusting said members horizontally with reference to the strings.

4. A device for modifying the tone of stringed instruments, comprising, a string supporting frame including cross bars, arms pivoted to the bars, a supporting member mounted on the arms, pivoted members carried by the supporting member, angular rods slidably mounted in the pivoted members, pressing members carried by the rods, said members being supported for horizontal and circular adjustment with reference to the strings.

5. A device for modifying the tone of stringed instruments, comprising, a string supporting frame including cross bars, arms pivoted to the bars, a supporting member mounted on the arms, a pivoted member carried by the supporting member, a bent rod slidably mounted in the pivoted member, a pressing member carried by the rod, said member being supported for horizontal and circular adjustment with reference to the strings, an additional arm secured to the supporting member, and a screw passed through said additional arm and bearing on said rod, whereby the pressure of the pressing member on the string can be regulated.

6. A device for modifying the tone of stringed instruments, comprising, a string supporting frame including cross bars, arms pivoted to the bars, a supporting member rigidly mounted on the arms, pressing members carried by said supporting member, a lever carrying a pressing member and pivoting around a rod integral with one of the cross bars and under control of said supporting member, for pressing the pressing members carried by said lever against strings relatively near one of the said cross bars of the frame.

In testimony whereof I affix my signature in presence of two witnesses.

GEORGES CLOETENS.
